UNITED STATES PATENT OFFICE.

MARCUS C. STEARNS, OF NEW YORK, N. Y.

DEVICE FOR DESTROYING SUBMARINES.

1,275,317.

Specification of Letters Patent. Patented Aug. 13, 1918.

Application filed June 16, 1917. Serial No. 175,072.

To all whom it may concern:

Be it known that I, MARCUS C. STEARNS, a citizen of the United States, and residing in the borough of Manhattan of the city of New York, have invented certain new and useful Improvements in Devices for Destroying Submarines, of which the following is a specification, reference being had to the accompanying drawings, forming a part hereof.

This invention relates to devices for destroying submarines in which a contact mine is intended to be released and set by the presence of a submarine and to be exploded upon contact therewith by the submarine. In devices of this general character it is desirable that the contact mine be maintained in safe condition against premature explosion until the immediate presence of a submarine in the waters about the mine makes it desirable for the mine to be set for explosion by contact therewith of the submarine. It is further desirable in devices of this character that they be readily visible upon the surface of the water by surface-going steamers so long as they are out of use, so that such steamers may, by observation, carefully avoid contact with them. Taking into account this requirement, the improved devices are adapted to float upon the surface of the water over an extended area, the many mines being bound together so as to form a network of vast area with which a submarine will necessarily contact when emerging in such area. In addition to the general advantages noted the improved device also provides for the automatic release of a signal upon contact of the submarine with the setting devices for the contact mines so that the presence of a submarine in the immediate waters will be indicated to patrols. A better understanding of the manner of incorporating the improved principles described in a system of great area will be better understood in connection with the detailed description of the embodiment shown in the accompanying drawings in which,—

Figure 1 is a schematic view in plan of a network of mines laid out in accordance with the present plan.

Fig. 2 is a view showing the manner in which the vast floating network will be maintained in position upon the surface of the water.

Fig. 3 is a detail view on a somewhat larger scale of one of the subareas of the network shown in Fig. 1.

Fig. 4 is a conventional view indicating a manner in which it is proposed that the destroying mines will be set by a submarine.

Fig. 5 is a detail view in section on a large scale of one of the mines showing it in its normal safe condition, taken on the plane indicated by the line 5—5 of Fig. 9.

Figs. 6, 7 and 8 are detail views of the manner of connecting the mine releasably to its retaining cable.

Fig. 9 is a detail view in plan of a jacket for one of the mines.

Figs. 10, 11 and 12 indicate somewhat conventionally the course taken by a mine after engagement of its retaining cable by a submarine upon emerging.

As indicated most clearly in the first four figures it is proposed that the improved devices shall be floated on the surface of the water and extend over a comparatively great area, their operation being dependent upon the emerging of a submarine in their particular zone. Fig. 4 shows, for instance, that when a submarine commences to emerge when under the vast network of mines proposed, its periscope or other superstructure will engage the cables forming the network now to be described.

As shown in Fig. 1 the network is comprised of a series of spider-web squares of the general form shown in Fig. 3, in which four stout cables *a* are connected to large floats *b* by which the cables and their attached mines are floated. These spider-web squares may be of any convenient area, depending upon manufacturing considerations, and may be connected one to another in any desired number depending upon the particular area of the sea which it is thought sufficient to protect. Each one of the squares thus formed has its spider-web structure formed of smaller running cables *c* extending through rings *a'* carried on the stout cables and fixed in position thereon normally by frangible connections, these smaller cables being extended toward the center of the square where there may be a stout ring *d* through which all of the smaller cables *c* may pass. As will appear later, it is desirable that the smaller cable *c* forming the spider-web in each square should be of a single running strand so that a disturbance

of it at any portion of its length will tend to pull it through the various rings for a greater part of its length and tear such rings, through their frangible connections 5 from their fixed anchorages on the stout cables and permit them to slide freely along such stout cables. This is the condition created whenever a submarine upon emerging 10 engages one of the smaller running cables *c* with its periscope or other elevated structure in some such manner as is indicated in Fig. 4.

Referring now to Fig. 5 for detailed description of the character of the mine used, 15 it will be seen that this mine is attached firmly to the cable *c* at its bottom. Each cable has attached to it a great number of these mines, as is shown in Figs. 1 and 3. Each mine being like every other mine, a 20 description of one will suffice for all. The invention is not to be limited, however, to the particular character of the mine, provided the general requirements noted herein be satisfied. The contact mine *e* is of 25 tubular form carrying in its upper end a hinged cover *f*, which is normally held closed by a spring-latch *f'* so as to insure the buoyancy of the mine and cause it to float in a substantially vertical position 30 above its retaining cable *c* and with its upper end somewhat above the surface of the sea. The form of retaining device for the mine is immaterial although that shown in detail in Figs. 6-8 will serve the purpose. 35 As shown therein there are two spaced lugs *g* affixed to the cable *c* and carrying a long rod *h* the ends of which rest in grooves *i* formed in proximate faces of slotted arms *k* of a bracket *k'* secured to the bottom of 40 the mine. The slot *k*² in the ends of the arms *k* communicates with the grooves *i* so that when the arms *k* rotate about the cable *c* through an angle of 180° the slots *k*² are brought into line with the retaining rod *h* 45 so that the arms may become disengaged from the rod and the mine thereby be released from the cable. The mine is attached to the cable *c* by means of a small cable *l* one end of which is secured loosely to the 50 cable between the lugs *g*, the other end of which is attached to the bracket *k'*. This cable *l* passes over the latch *f'* for the cover *f* so that when the cable *c* is pulled violently the lugs *g* will in turn impress a pull on the 55 cable *l* sufficient to trip the latch *f'* and permit the cover *f* under the influence of a spring *f*² to fly open. Normally, the mine in its upright floating position is incased completely in a cylindrical jacket *m* which 60 protects the caps *e'* and prevents accidental contact therewith by any portion of the improved destroying devices or by any vessels on the surface. Within the cover *f* of the mine may be inclosed conveniently suitable 65 signaling devices intended to indicate to the

presence of a submarine. These signaling devices may be of any desired character but are shown herein as comprised of a balloon *n* which may be connected by a cord *o* with the mine. This balloon is then 70 retained until the mine is exploded by contact of the submarine therewith, the release of the balloon in this manner being an absolute indication of the exact location of the submarine. There may also be a rocket 75 flare *p* or other light signal carried within the cover *f* and this signal may be set off by frictional engagement of a cap *f*³ on the edge of the cover with the head of the latch *f'*, upon release of the latter. 80

From the foregoing description of the details of construction the intended mode of operation of the improved destroying devices should be clear. Normally, the vast network of cables is supported near the surface of the 85 sea by the large float *b*. The buoyancy of the mines *c* at this time is such as to maintain them in vertical position above their retaining cables and somewhat above the surface of the sea, the air-tight closure of the 90 mine by the cover *f* serving to preserve this buoyancy. If a submarine now emerges within the zone covered by the cables or, indeed, attempts to pass under these cables in 95 proximity thereto, the periscope or other superstructure will engage one of the lighter cables *c* in one of the squares and exert such a tremendous pull on this cable as to communicate, in turn, a pull on the latch string *l* of many of the mines of the square. When 100 the latch *f'* is tripped in each such mine the cover *f* will fly open under the action of the spring *f*², the opening being accompanied by ignition of the rocket *p* by engagement of the cap *f*³ with the nose of the latch *f'*. This signal will give the first indication of the 105 presence of a submarine. When the cover *f* is open the balloon *n* within the cover will be free to rise and, being united permanently with the mine *e*, will maintain its position 110 directly over the square in which the submarine is operated. Upon the opening of the air-tight cover *f* the mine and casing, 115 will, of course, lose its buoyancy and tend to sink being of greater specific gravity than water. It will then rock about its retaining cable *c* until it is in the depending position shown in Fig. 10, when the slots *k*² in the retaining arms *k* will become disengaged from the retaining rod *h*, thereby permitting the 120 mine to fall bodily away from the cable. The safety shell *m* having no physical connection with the mine will drop away from the mine in some such manner as is indicated in Fig. 11, thereby exposing the caps *e'* to contact. The mine *e* will sink to a depth determined by its securing cable *l* and hang depended as shown in Fig. 12. In this condition, with the casing *m* removed and in 125 this position some distance below the surface 130

of the sea, the many mines thus released by the submarine will, with almost absolute certainty, present an unavoidable target. Further slight movement of the submarine 5 beneath the square from which the mines are thus released will most certainly bring it into contact with caps e' of one or more of these mines and thereby insure its destruction. The signals given upon the release of 10 each such mine in the form of the balloon n and the rocket p will attract the attention of patrols and bring them immediately to the scene whether it be night or day, so that even should the submarine fail to contact 15 with one of the mines its presence will be known with certainty and, being thus located, the chances of its ultimate destruction become great.

When the mines are floating in their normal positions entirely incased by their jackets m they will be visible to surface-going vessels and so may be avoided and their danger of premature explosions by any disturbing elements is minimized by the presence of the 25 jackets. The particular means employed for setting the mines in condition and in position for explosion are such as practically to require the presence of an undersea boat operating in some such manner as has been 30 described. The two elements then of safety to surface-going craft bound on legitimate business and certainty of operation as against undersea craft are thus embodied in the one construction.

35 The scope of the invention will appear from the appended claims.

I claim as my invention:

1. A device for destroying submarines comprising a running cable, means to float the 40 cable, a mine secured to the cable, and devices for releasing and setting the mine adapted to be actuated by engagement of a submarine with the running cable.

2. A device for destroying submarines comprising a running cable, means to float the 45 cable, a mine secured to the cable, devices for releasing and setting the mine adapted to be actuated by engagement of a submarine with the running cable, and a jacket incasing the mine and dislodged upon release 50 of the mine from the cable.

3. A device for destroying submarines comprising a running cable, means to float the cable, a mine secured to the cable, an air 55 chamber formed in the mine to float it, devices for releasing the air from said chamber adapted to be actuated by engagement of a submarine with the running cable, thereby permitting the mine to sink below the 60 cable for contact by the submarine.

4. A device for destroying submarines comprising a running cable, means to float the cable, a mine secured to the cable, an air chamber formed in the mine to float it, devices for releasing the air from said chamber 65

70 adapted to be actuated by engagement of a submarine with the running cable, thereby permitting the mine to sink below the cable for contact by the submarine, and a jacket incasing the mine and dislodged upon release of the mine from the cable.

5. A device for destroying submarines comprising a running cable, means to float the cable, a mine secured to the cable, an independent flexible connection between the cable 75 and the mine, an air chamber formed in the mine to float it, devices for releasing the air from said chamber adapted to be actuated by engagement of a submarine with the running cable thereby permitting the mine to 80 sink below the cable for contact by the submarine, said flexible connection serving to arrest the movement of the mine at a predetermined depth below the surface.

6. A device for destroying submarines comprising a running cable, means to float the cable, a mine secured to the cable, an air chamber formed in the mine to float it above 85 the cable, said securing means for the mine being releasable automatically when the mine sinks below the cable, devices for releasing the air from said chamber adapted to be actuated by engagement of a submarine with the running cable thereby permitting the mine to sink below the cable for contact by 90 the submarine, an independent flexible connection between the mine and the cable for arresting the movement of the mine at a predetermined depth.

7. A device for destroying submarines comprising a running cable, means to float the cable, a tubular mine secured to the cable, an air-tight cover hingedly supported on one end of the tubular mine to form an air chamber to float the mine, a latch for holding the 105 cover closed, and a connection between the latch and the running cable whereby when the running cable is moved by engagement therewith of a submarine the latch will be released to open the cover and permit the 110 mine to sink.

8. A device for destroying submarines comprising a running cable, means to float the cable, a mine secured to the cable, an air chamber formed in the mine to float it, devices for releasing the air from said chamber adapted to be actuated by engagement of a submarine with the running cable, thereby permitting the mine to sink below the cable for contact by the submarine, and a balloon 115 attached to the mine and released simultaneously therewith to mark its position.

9. A device for destroying submarines comprising a running cable, means to float the cable, a mine secured to the cable, an air 125 chamber formed in the mine to float it, devices for releasing the air from said chamber adapted to be actuated by engagement of a submarine with the running cable, thereby permitting the mine to sink below the cable 130

for contact by the submarine, and a rocket flare ignited automatically upon release of the mine.

10. A device for destroying submarines comprising a series of squares interlocked and each comprising four stout cables, running cables extending in each square from the stout cables to the center thereof, a ring through which the running cable passes at 10 the center, floats to support all of the squares, mines attached to each running cable, and devices for releasing and setting the mines adapted to be actuated by engagement of a submarine with their respective 15 running cables.

11. A device for destroying submarines comprising a running cable, means to float the cable, an explosive mine secured to the cable and having exposed caps on its sides, a 20 metal jacket incasing the mine and open at its lower end and adapted to slip off the mine when the latter reverses its position and sinks below the cable, and devices for releasing the mine from the cable adapted to 25 be actuated by engagement of a submarine with the moving cable to permit the mine to sink for contact therewith by the submarine.

12. A device for destroying submarines

comprising a running cable, means to float 30 the cable, a plurality of mines secured to the cable, an air chamber formed in each mine to float it, devices for releasing the air from the chambers of a plurality of said mines adapted to be actuated by engagement of a 35 submarine with the running cable, thereby permitting the mines having such released chambers to sink below the cable for contact with one or more of such released mines by the submarine, and means for recovering the 40 unexploded mines.

13. A device for destroying submarines comprising a series of squares interlocked and each comprising four stout cables, running cables extending in each square from 45 the stout cables to the center thereof, a ring through which the running cable passes at the center, floats to support all of the squares, mines attached to each running cable, devices for releasing and setting a plurality of such mines adapted to be actuated by engagement of a submarine with their respective running cables, and means for recovering the unexploded mines.

This specification signed this 11th day of 55 June A. D. 1917.

MARCUS C. STEARNS.
